UNITED STATES PATENT OFFICE.

THOMAS F. FINN, OF NORTH ANDOVER, MASSACHUSETTS.

STOP MECHANISM FOR LOOMS.

1,353,824.

Specification of Letters Patent. Patented Sept. 28, 1920.

Application filed May 29, 1920. Serial No. 385,330.

To all whom it may concern:

Be it known that I, THOMAS F. FINN, a citizen of the United States, residing at North Andover, in the county of Essex and State of Massachusetts, have invented new and useful Improvements in Stop Mechanism for Looms, of which the following is a specification.

This invention relates to a stop motion for looms.

The object of the invention is to provide a simple mechanism for automatically stopping a loom in the event that the filling thread breaks or becomes exhausted.

The invention consists in the combination and arrangement of parts set forth in the following specification and particularly pointed out in the claims thereof.

Referring to the drawings:

Figure 1 represents a side elevation of a portion of a loom, the lay being shown in section, my improved stop mechanism being embodied therein.

Fig. 2 is a plan view of a portion of the mechanism, the breast beam being broken away to save space in the drawings and to enable both ends of the release rod to be illustrated.

Fig. 3 is a detail front elevation of the release rod.

Fig. 4 is a detail section taken on the line 4—4, of Fig. 2.

Like numerals refer to like parts throughout the several views of the drawings.

In the drawings, 5 represents one of the side frames of a loom, 6 the breast beam and 7 the lay. Fast to the breast beam 6 midway of said beam is a bracket 8 which is provided with arms 9 and 10, and to the arm 9 is adjustably fastened by a bolt 11 a cam 12. Fast to the arm 10 is a stud 13 upon which is pivotally mounted a tumbler 14, which is normally held by a spring 15 in the position illustrated in Fig. 1, at which time an end 16 thereof abuts against a stop 17 provided upon the arm 9, and a portion of said end 16 projects above a top edge 18 of the arm 9. The spring 15 is coiled around the stud 13 and one end of said spring contacts with a projection 19 upon the tumbler 14 while the other end projects into a collar 20 which is adjustably mounted upon the stud 13.

Fast to lay 7 is a bracket 21 which is pro-

vided with ears 22 between which is mounted upon a shaft 23 a rocking member 24 to which are secured a plurality of feeler wires 25. The feeler wires 25 project above a groove 26 provided in the upper surface of the lay. Fast to the shaft 23 is an arm 27 which is connected by a rod 28 with a dagger socket 29 pivoted at 30 to a portion of the bracket 21. A dagger 31 is secured to the socket 29 and is bent to project over the arm 9 and cam 12. A spring 32 acts to hold the dagger 31 upon the cam 12 and tends to cause the dagger to follow the curve of the cam as the lay oscillates.

In stopping the operation of the loom, it is necessary to disconnect the friction driving members which transmit the power and also operate a band brake mechanism thereby stopping the momentum of the loom. Fast to a shaft 33 which extends between the side frames 5 of the loom is a shipper handle 34 which has formed integral therewith at its lower end an arm 35 from which projects a pin 36 which engages a lever 37 pivoted at 38 to the frame 5. The lower end of the lever 37 has a shipper rod 39 attached thereto, the said shipper rod being connected with the movable member of the friction driving mechanism not illustrated in the drawings but well known to those skilled in the art.

The band brake also not illustrated in the drawings is operated by the movement of a foot treadle 40, the forward end of which is illustrated in Fig. 1. Attached to the foot treadle 40 at 41 is a treadle rod 42 which has a locking member 43 attached to its upper end, the said locking member constituting a part of said treadle rod and projecting through a slot provided in a guiding member 44 fastened to the frame 5 of the loom. A spring 45, the tension of which may be adjusted by a movable collar 46, rests on a bracket 47 fastened to the frame 5 of the loom, and tends to keep the foot treadle 40 in a raised position, at which time the friction band is held tight around the brake wheel. When the foot treadle 40 is pressed downwardly, the spring 45 is compressed and the brake released and the whole mechanism is held in this position by means of a key 48 which projects into a notch 49 provided in the locking member 43 as illustrated in Fig. 4. A flat spring 50 at-

tached to the upper end of the treadle rod 42 contacts with the rear of the guide member 44 when the locking member 43 is lowered and presses the latter forward so that 5 the jar of the loom will not allow the treadle rod to become accidentally disengaged and the brake applied while the loom is running. Fast to the treadle rod 42 is a knock-off cam 51 which is so positioned that when 10 the treadle rod 42 is released it will hit the lower end of the arm 35 of the shipper handle 34 which is then in the position illustrated in dotted lines, Fig. 1, thereby releasing said handle and thus shutting off 15 the power.

All of the mechanism thus far described is old and well known in the art, being a portion of the equipment of the Knowles loom. The novel feature of this invention 20 lies in the mechanism which is provided for releasing the locking member 43 from the key 48 and thereby simultaneously applying the band brake and operating the shipper handle to disconnect the power. This mechanism 25 is as follows:—Extending longitudinally of the breast beam 6 from a point approximately midway its length to a point adjacent to the treadle rod 42 is a release rod 52 which is supported in a plurality of 30 bearings 53 which are attached to the breast beam 6. The outer end of the release rod 52 is bent upwardly at 54 and said upturned end is located directly in front of the upper end of the locking member 43. 35 The inner end of the release rod 52 is bent downwardly at 55 and is again bent to terminate in a short portion 56 which is parallel to the main portion of the rod. The portion 56 has a rod 57 attached 40 thereto which has screw-threaded engagement with a member 58 which in turn is secured to the tumbler 14 at 59. By removing the member 58 from the tumbler 14 and turning said member upon the rod 57, the 45 end 54 of the release rod 52 may be correctly positioned relatively to the locking member 43. When the tumbler 14 is engaged by the 50 dagger 31 causing the tumbler to be rocked upon the stud 13, a rocking movement is imparted to the release rod 52 and the end 54 thereof is caused to engage the upper end of the locking member 43 and force said member out of engagement with the key 48. 55 The general operation of my improved 60 stop motion is as follows: In starting the loom the foot treadle 40 is pressed downwardly, thereby releasing the band brake. The foot treadle 40 is held in its lowermost position by means of the key 48 projecting into the notch 49 of the locking member 43, being held in engagement therewith by the spring 50. The shipper handle 34 is then moved from the full line position to the dotted line position in Fig. 1, thereby rocking 65 the lever 37 and causing the shipper rod 39

to throw on the power. Each time that the lay 7 moves back from the fell of the cloth, or in other words, away from the breast beam 6, the dagger 31 contacts with the cam 12 and acts to lift the dagger socket 29 and thereby raise the feeler wires 25 to a sufficient height for the shuttle to pass therebeneath and deposit the filling thread between the warp threads in a manner well known to those skilled in the art. 75

When the lay 7 again beats up or moves toward the breast beam 6 the feeler wires 25 will swing downwardly as the dagger 31 moves over the surface of the cam 12, and if the filling thread is unbroken between 80 the warp threads, the feeler wires 25 will be supported by said filling thread above the groove 26 and will hold the dagger 31 above and out of contact with the end 16 of the tumbler 14. If, however, the filling thread 85 is broken or has become exhausted in the shuttle, as the lay 7 beats up, the feeler wires 25 will not be supported by the filling thread which will cause the dagger 31 to drop and rest upon the upper edge 18 of 90 the arm 9 and the continued movement of the lay will cause the dagger 31 to engage the end 16 of the tumbler 14 and rock said tumbler, the rocking movement of which will be transmitted through the connecting 95 rod 57 to the release rod 52, thereby forcing the upturned end 54 of the release rod 52 against the upper end of the locking member 43 and forcing said locking member out of engagement with the key 48. The treadle 100 rod 42 being thus released will be forced upwardly by the spring 45 thereby pulling the foot treadle 40 upwardly and applying the brake mechanism. During the upward movement of the treadle rod 42 the knockoff 105 cam 51 will engage the lower end of the arm 35 of the shipper handle 34 thereby forcing the said shipper handle from the position illustrated in dotted lines, Fig. 1 to the position illustrated in full lines, and thereby 110 shutting off the power. 110

I claim:

1. A stop motion for looms embodying therein a shipper handle adapted to control the power for the loom, a treadle rod adapted to control a brake, means to lock said treadle rod to hold said brake in a released position, a release rod adapted to engage said treadle rod, a tumbler operatively connected with said release rod and means controlled by the filling thread adapted to rock said tumbler and thereby impart a rocking movement to said release rod, whereupon said treadle rod and shipper handle will be operated simultaneously to stop the loom. 115

2. A stop motion for looms embodying therein a shipper handle adapted to control the power for the loom, a treadle rod adapted to control a brake, means to lock said treadle rod to hold said brake in a released 120 position, a release rod adapted to engage said treadle rod, a tumbler operatively connected with said release rod and means controlled by the filling thread adapted to rock said tumbler and thereby impart a rocking movement to said release rod, whereupon said treadle rod and shipper handle will be operated simultaneously to stop the loom. 125

position, a release rod, one end of which is provided with an upwardly extending arm adapted to engage said treadle rod, a tumbler, means connecting said tumbler with 5 said release rod and means controlled by the filling thread adapted to rock said tumbler and thereby impart a rocking movement to said release rod, the upwardly extending arm of said release rod being rocked against 10 said treadle rod to force said treadle rod out of engagement with said locking means, whereupon said treadle rod and shipper handle will be operated simultaneously to stop the loom.

15 3. A stop motion for looms embodying therein a shipper handle adapted to control the power for the loom, a treadle rod adapted to control a brake, means to lock said treadle rod to hold said brake in a released 20 position, a release rod, one end of which is provided with an upwardly extending arm adapted to engage said treadle rod, and the other end thereof provided with a downwardly extending arm, a tumbler, means 25 connecting said tumbler with said downwardly extending arm and means controlled by the filling thread adapted to rock said tumbler and thereby impart a rocking movement to said release rod, the upwardly extending arm of said release rod being rocked against 30 said treadle rod to force said treadle rod out of engagement with said locking means, whereupon said treadle rod and shipper handle will be operated simultaneously to stop the loom.

per handle will be operated simultaneously to stop the loom.

35

4. A stop motion for looms embodying therein a shipper handle adapted to control the power for the loom, a treadle rod adapted to control a brake, means to lock said treadle rod to hold said brake in a released 40 position, a release rod, one end of which is provided with an upwardly extending arm adapted to engage said treadle rod, and the other end thereof provided with a downwardly extending arm, a tumbler, means 45 connecting said tumbler with said downwardly extending arm, means to vary the length of said connecting means and thereby position said upturned arm relatively to said treadle rod and means controlled by 50 the filling thread adapted to rock said tumbler and thereby impart a rocking movement to said release rod, the upwardly extending arm of said release rod being rocked against said treadle rod to force said treadle rod 55 out of engagement with said locking means, whereupon said treadle rod and shipper handle will be operated simultaneously to stop the loom.

In testimony whereof I have hereunto set 60 my hand in presence of two subscribing witnesses.
